UNITED STATES PATENT OFFICE

RILEY J. AULTMAN, OF CLARK'S, OHIO.

MACHINE FOR MANUFACTURING FENCES.

SPECIFICATION forming part of Letters Patent No. 340,476, dated April 20, 1886.

Application filed November 28, 1885. Serial No. 184,209. (No model.)

To all whom it may concern:

Be it known that I, RILEY J. AULTMAN, a citizen of the United States, residing at Clark's, in the county of Coshocton and State of Ohio, have invented certain new and useful Improvements in Machines for Manufacturing Fences, of which the following is a specification, reference being had therein to the accompanying drawings.

10 My invention relates to improved fence-making machines.

The object of the invention is to produce a simple and cheap machine which shall be light, portable, and by which a fence may be 15 made at the place where it is designed to be used.

The kind of fence which it is my object to manufacture is one in which series of pickets or slats are woven into place by wires, which, 20 in connection with the pickets, form the fence.

To the accomplishment of the above the invention consists in the novel construction and arrangement of the device for holding the picket in position while the wire strands are 25 being twisted therearound, and in the combination, with such device, of the strand-twister, as will be described and claimed hereinafter.

In order that those skilled in the art to 30 which my invention relates may know how to make and use the same, I will now proceed to describe it in connection with the accompanying drawings, in which—

Figure 1 is a sectional view showing the arrangement and manner of operating the wire-twisting wheels. Fig. 2 is a side elevation of 35 the machine in position for work, and also showing the section of completed fence; and Fig. 3, a front elevation of the device.

In the drawings, A A represent uprights, 40 upon which are mounted wheels B, provided with holes b, of a number corresponding with the strands of wire employed at each point of binding the slats. The frame is mounted upon any suitable piece, C, which may be provided with wheels, if desired, or so formed 45 as to slide readily over the ground, in order to change the position of the machine as the frame is formed.

D represents wires, which are placed in pairs, 50 and any number of the pairs may be employed to render the frame sufficiently rigid. These wires are passed through the wheels B, and

are twisted by turning the said wheels. The preferred means of operating these wheels is shown in Fig. 1. This consists in providing 55 the wheels with projections c upon their periphery, which are engaged by an endless chain, E, which receives motion through the wheel F, which is provided with a handle, G.

H represent levers, which are mounted in 60 projections I from the main frame of the machine, and these projections are provided with a series of holes, i, for the reception of a pin, upon which the levers are fulcrumed, the number of holes allowing the levers to be 65 mounted at any desired distance from the frame. These levers are connected at their inner ends, and at this point they are provided with a handle, J, for moving them in or out, for the purpose hereinafter set forth, and they 70 are pivoted at the point J, so as to allow their inner ends to be moved in or out. At points near their outer ends each lever H is provided with a pin, L, secured to the lever at right angle to the side thereof, as clearly 75 shown in Fig. 3. When the levers are operated to force their outer ends toward the pickets, these pins L come in contact with the pickets, and serve to hold them securely in 80 place.

K represents a stop placed at any desired point upon the side piece, and each picket, as it is placed in the fence, has its position determined by being rested upon this stop.

In the operation of the machine the wires 85 D are first stretched from the starting-point to any suitable distance and drawn taut, they being passed through the holes b in the wheels B of the machine. When the parts are in this position, the pickets are introduced between the members of the several pairs of the double strand of wire. In placing the picket 90 in position it is first rested upon the stop K, to determine its height, and when the machine is ready for the reception of this picket 95 the levers H are in the position shown in dotted lines in Fig. 2. In this position the pins L, upon their ends, are in position to engage with the picket when it is placed upon the stop K. After the height of the picket has been determined, the handle J, placed at the juncture 100 of the inner ends of the levers H, is forced inward toward the machine, thus carrying their outward ends and the pickets with them.

When the picket has been placed, the handle G is given two or three revolutions, and thus motion is communicated through the chain E and wheels B to the wires, which are thereby 5 twisted, and in this way the pickets are retained in place.

Having thus described my invention, what I claim is—

1. In a fence-making machine, the combination, with a suitable upright provided with a stop, K, and suitable brackets or projections, I, of levers H, pivotally mounted near their outer ends in said brackets or projections, pivoted to each other at their inner ends, and 15 provided with handle J and pins L, as and for the purpose set forth.

2. In a fence-making machine, the combination, with suitable frames and wire-twisting wheels mounted therein, of projections or brackets I, secured to the frame, levers H, pivoted in said brackets or projections and provided with pins L and handle J, and stop K, secured to the frame, as and for the purpose set forth.

In testimony whereof I affix my signature in 25 presence of two witnesses.

RILEY J. AULTMAN.
